SUPPORTING STRUCTURE FOR TRANSFORMER WINDINGS

Douglas H. Harse, North Syracuse, N. Y., assignor to General Electric Company, a corporation of New York

Application April 22, 1952, Serial No. 283,630

4 Claims. (Cl. 336—198)

My invention relates to a supporting structure for transformer windings, and has particular utility as applied to a structure for supporting one or more turns of auxiliary windings on a high-voltage universal sweep transformer suitable for television scanning circuits and the like.

In television line-scanning circuits, it is common practice to employ a universal sweep transformer of the core type which not only includes the usual windings for energizing deflection and accelerating elements of the picture tube, but also one or more auxiliary windings, usually of one turn each, for energizing filament heating circuits and the like.

It has often been the practice, in transformer assemblies of this type, merely to loop these auxiliary transformer windings around one of the transformer core members. Unless special supporting means are provided, this has the disadvantage that the auxiliary windings may move about or be deformed under the influence of gravity or vibration. Consequently, these windings may come in close contact with either the transformer core or with other transformer windings, or both. Furthermore, since transformers of this type generally carry high voltages, the likelihood of insulation breakdown between the auxiliary windings and the core, or between windings, is greatly increased by the likelihood of close physical contact therewith.

It is desirable, therefore, to provide means for securely holding the auxiliary windings in such a position that they are properly spaced from the core and prevented from coming in contact with either the transformer core or the other transformer windings.

Thus, one of the primary objects of my invention is to provide an improved supporting structure for retaining transformer windings in definite spaced relation with respect to both the core and the other windings.

Another object of my invention is to provide an improved transformer lead-supporting structure.

A further object of my invention is to provide a simple and inexpensive transformer lead-supporting structure that lends itself readily to mass production manufacture.

Briefly stated, in accordance with one aspect of my invention, I provide a lead-supporting structure formed of two interlocking members, at least one of which is composed of an insulating sheet material and is arranged to support the windings, and the other of which is arranged to surround a leg of the transformer core. More specifically, I provide a generally L-shaped lead-supporting member of an insulating material which is held firmly to the transformer core by means of a generally rectangular clamping ring member, preferably also of a similar insulating material.

My invention will be better understood from the following description taken in connection with the accompanying drawing and its scope will be pointed out in the appended claims.

In the drawing:

Fig. 1 is a front elevation view of a transformer assembly containing my supporting structure;

Fig. 2 is a detailed perspective view, partly in section, of part of the assembly shown in Fig. 1;

Fig. 3 is a detailed perspective view of the components of the supporting structure of Figs. 1 and 2; and

Fig. 4 is a detailed perspective view of an assembly similar to that shown in Fig. 2, but having an alternate form of transformer core.

Referring now to Fig. 1, there is shown a transformer

2

assembly whose core legs comprise a pair of generally U-shaped core members 10, 11 which are positioned in opposed relation so as to define a generally rectangular window 12 therebetween. The cores may be of ferrite or powdered magnetic material and may have the usual principal windings 13, 14 supported on their upper ends. The whole assembly is clamped between insulating side panels 15 in any suitable manner (not shown in detail). This transformer core and winding assembly may, for example, be generally similar to that shown and described in the copending application of Charles E. Torsch, Serial No. 95,852, filed May 27, 1949, now Patent No. 2,639,319, and assigned to the same assignee as the present invention. Since the details of this construction, as thus far described, form no part of the present invention, connecting leads and terminals for the principal windings have been omitted from Fig. 1 to simplify the drawing.

In Fig. 1, three single-turn auxiliary windings 16 are shown for purposes of illustration, surrounding the right-hand core section 11. In accordance with my invention, the auxiliary turns 16 are held in place by a lead-retaining member 17. Member 17 is a generally L-shaped member of insulating material situated within the plane of window opening 12 and having a first or horizontal leg disposed along the entire length of the base of opening 12 such that its ends abut against the vertical portion of the core members 10 and 11, thereby preventing any movement in the horizontal plane along the base.

Member 17 also has a vertically-extending portion containing a plurality of vertically-spaced holes 18. As is best shown in the detailed perspective view of Fig. 2, these holes 18 are aligned in horizontal planes with corresponding vertically-spaced holes 19 and 20 in the side panel 15. Each set of holes in a horizontal plane is arranged to accommodate and hold one of the insulated conductors 16 in position. While the rows of holes are preferably aligned as shown, they may, of course, be arranged in other configurations. In any event, they are arranged so as to position the transformer leads at a location providing proper inductive coupling and permitting easy access to the conductors for connections to other circuits.

The lead-retaining member 17 is held against twisting or sidewise movement by means of a generally rectangular, closed, clamping ring member 21 which is interlocked with it and provided with a rectangular aperture. Member 21 fits closely about one end of core member 11 in assembled position and is restrained against transverse rocking movement on the core by virtue of the close fit between them.

As is best shown in Fig. 3, lead-supporting member 17 is provided with a notch 22 which, in its normal assembled relationship, cooperates with a notch 23 in clamping ring member 21. When the notches are engaged, members 17 and 21 are thereby rigidly in position in mutually-transverse planes.

As best seen in Fig. 1, member 21 is located at a point along the horizontal portion of member 17 so that, when the structure is assembled, ring 21 surrounds one of the core members near its free end and just to one side of the air gap between the two core members 10, 11.

The widths of the interlocking notches 22 and 23 will be determined by the thickness of the sheet material used. The depths of these notches may vary but are preferably about one-half the depth of the material where the opposing portions of member 17 and ring 21 are of the same depth.

To assemble the lead-supporting assembly on the transformer core, member 17 and clamping ring 23 are placed so that their respective notches 22 and 23 interlock. One of the transformer core members 10, 11 is next threaded into the clamping ring 21, as shown in Fig. 2, thereby preventing the notched members 17 and 21 from separating. Finally, the second core member 10 is positioned in opposed relation to the first core member 11.

As will be seen from Fig. 1, the lead retainer 17 will be prevented thereby from sliding off the core member 11

because the end of member 17 abuts the inner surface of its vertical portion.

When the lead-retaining assembly 17, 21 is assembled in proper position, as shown in Figs. 1 and 2, the single-turn windings 16 are threaded into the transformer assembly through the holes 19 or 20 in one side panel 18, then through holes 18, and finally out through the other holes 20 or 19 in the side wall 15.

This assembly provides an improved assembly particularly adapted for supporting one or more turns of transformer windings in spaced relation about one core leg of the transformer, so that air insulation is provided between these windings, the transformer core members and other transformer windings. This reduces the danger of insulation breakdowns, and makes it possible to cover the auxiliary windings with an insulating material of less critical breakdown properties than would otherwise be required.

It will also be seen that I have provided a lead retaining assembly that can be readily assembled and disassembled and which can be readily adapted for use with many types of transformers as well as with the specific type of transformer shown with this preferred form of my invention. Although my invention has been described in conjunction with a transformer having a core of rectangular cross section, for example, it may be used with cores having other cross-sectional configurations. By way of illustration, Fig. 4 shows an optional form of my invention, comprising retaining member 17' and clamping ring 21' having an octagonal window therein to receive a transformer core member 11' having an octagonal cross section. The portions of Fig. 4 bearing the numerals designated prime correspond to the portions of Fig. 2 having similar numerals.

While the present invention has been described by reference to particular embodiments thereof, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States is:

1. A transformer having a closed core whose legs define a generally rectangular window and a supporting structure for windings of the transformer comprising a generally L-shaped lead-supporting member of insulating material having a first leg fitted closely against one leg of the core within said window and abutting against a portion of said core whereby it is restrained against axial movement relative to said core and a second leg extending in a generally transverse direction within said window, said second leg having one or more conductor-supporting apertures formed therein, and interlocking means for retaining said lead-supporting member in position against said one leg in said window, said interlocking means comprising a closed clamping-ring member of insulating material closely surrounding a leg of said core, said two members having closely interfitting interlocking notches in adjacent edges thereof to hold them rigidly in mutually-transverse planes on said core. 60

2. The combination of a transformer having a closed core whose legs define a rectangular window opening and a structure for supporting auxiliary windings, said structure comprising a generally L-shaped, flat, lead- 65

retaining member of insulating material situated within the plane of the transformer window opening, said retaining member having a first leg disposed along one side of the transformer window opening and abutting 5 against the perpendicular sides of said core at both ends, said first leg having a notch in its top portion and a raised portion at one end constituting a second leg lying alongside of one of said perpendicular sides, said second leg containing therein one or more spaced lead-retaining holes, and a closed, clamping-ring member of insulating material closely surrounding a leg of said core and said lead-retaining member, said ring member having a notch in its inner surface constructed and arranged to interlock with the notch in the lead-retaining member thereby 15 securing it to said core.

3. In a high-voltage television sweep transformer of the type having one or more auxiliary windings and a pair of opposing U-shaped core members of polygonal cross section defining a generally rectangular window 20 opening, the improvement comprising a generally L-shaped, conductor-supporting member composed of insulating sheet material situated within the plane of said transformer window opening, said supporting member having a horizontal first leg disposed along the entire 25 base of said transformer window opening and abutting against the vertical core portion at either end, said first leg having a notched top portion near its center, said supporting member having a vertical second leg at one end extending alongside one of the vertical core portions, said vertical leg having one or more spaced lead-receiving holes therethrough, and a closed, clamping-ring member of insulating material having a window opening shaped closely to surround a leg of one of said core members, said clamping-ring member having a notched 30 to 35 inside top portion constructed and arranged to interlock with said first notch portion in the top of said conductor supporting member.

4. In a transformer of the type having a closed core whose legs define a window opening, the improvement 40 comprising a structure for supporting auxiliary windings relative to said transformer, said structure comprising a generally L-shaped lead-supporting member of insulating material having a first leg and a raised portion constituting a second leg, said first leg having a notched 45 top portion, said second leg having one or more conductor-supporting apertures formed therein, and interlocking means for retaining said lead supporting member in a predetermined position in a transformer window, said interlocking means comprising a closed clamping-ring member of insulating material adapted and arranged 50 closely to surround said first leg of said lead supporting member and the leg of a transformer core, said clamping-ring member having a notched inner surface constructed and arranged to interlock with the notch in the top of said lead-retaining member, whereby said lead supporting member may be secured to the leg of the 55 transformer core.
